PAPER TUBE SLITTER

Lambert Flieger, Morton Grove, Ill., assignor to
Standard Cap and Seal Corporation, Chicago,
Ill., a corporation of Virginia

Application March 10, 1950, Serial No. 8,449

Term of patent 14 years

(Cl. D22—3)

To all whom it may concern:

Be it known that I, Lambert Flieger, a citizen of the United States, residing at Morton Grove, State of Illinois, have invented a new, original, and ornamental Design for Paper Tube Slitter, of which the following is a specification, reference being had to the accompanying drawing, forming a part hereof.

Figure 1 is a top plan view of a paper tube slitter, showing my new design.

Figure 2 is a bottom plan view thereof.

Figure 3 is a side elevational view of the paper tube slitter shown in Figure 1.

Figure 4 is a sectional view taken on line 4—4 of Figure 3.

Fig. 5 is a rear view thereof with parts in sec-

tion and showing a paper tube in dotted lines for purposes of illustration, the section being taken on line 5—5 of Fig. 3.

I claim:

The ornamental design for a paper tube slitter, as shown and described.

LAMBERT FLIEGER.
